CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is an opposite side bottom rear perspective view thereof.

The broken line surrounding the tread elements defines the peripheral bounds of the claimed design and forms no part thereof. The broken line showing of the seven tread tips form no part of the claimed design. The unshaded regions within the peripheral boundary form no part of the claimed design. The broken lines depicting the remainder of the shoe show features that form no part of the claimed design.
